W. DUNSON.
ADJUSTABLE SHADE AND BLIND HOLDER.
APPLICATION FILED NOV. 11, 1920.

1,405,400.

Patented Feb. 7, 1922.

INVENTOR.

WILLIAM DUNSON.

BY

El. Bradford

ATTORNEY.

UNITED STATES PATENT OFFICE.

WILLIAM DUNSON, OF INDIANAPOLIS, INDIANA.

ADJUSTABLE SHADE AND BLIND HOLDER.

1,405,400.

Specification of Letters Patent. Patented Feb. 7, 1922.

Application filed November 11, 1920. Serial No. 423,416.

To all whom it may concern:

Be it known that I, WILLIAM DUNSON, a citizen of the United States, residing at Indianapolis, in the county of Marion and State of Indiana, have invented certain new and useful Improvements in Adjustable Shade and Blind Holders, of which the following is a specification.

This invention relates to adjustable shade and blind holders, and the prime feature of the invention is the provision of brackets which may be attached to parts of the window frame without unduly marring or defacing the frame, and is adjustable so that it will fit any ordinary width of frame.

A further feature of the invention is in so constructing the holder that the parts thereof may be stamped or formed from sheet metal or tubing, the number of parts being reduced to a minimum, and being adjustably connected with each other.

A further feature of the invention is in so constructing the various parts of the holder that curtains, trimmings of various kinds and blinds may be supported from the same brackets.

Other objects and advantages will be hereinafter more fully set forth and pointed out in the accompanying specification.

In the accompanying drawings which are made a part of this application,

Figure 1 is a front elevation of one of the brackets showing the same applied to use on a window frame,

Figure 2 is a top plan view of one of the brackets showing the frame in section,

Figure 3 is an end elevation of the bracket, and

Figure 4 is a sectional view as seen on line 4-4 Figure 2.

Referring to the drawings, 1 indicates a frame which may be constructed in the usual or any preferred manner to which is attached a bracket 2, said bracket comprising a pole supporting arm 3 and an anchoring member 4, the arm 3 having a body portion 5, one end of which is bent at right angles, as shown at 6, and extends over one edge face of the frame 1, a nail or screw 7 being driven through the angular extension for securing it to the frame. The anchoring member 4 is formed from a section of metal which is doubled upon itself, the arm thereof adjacent the face of the frame 1 having channels 8 at its edges for the re-

ception of the end of the body 5 of the arm 3. The integral ends of the folded over portions of the anchoring member 4 are bent at right angles as shown at 8', so that said angular extension will fit over the opposite edge of the frame 1 from the member 6 a nail or screw 9 being employed for securing this end of the anchoring member to the frame.

The outer end of the arm 3 is provided with a downwardly bowed portion 10 for the reception of the usual form of curtain pole 11, the outer end of the arm 3 being bent upon itself, and the extreme end thereof formed into a pin 12 for engagement with a curtain rod 13, the bent over end 14 of the arm 3 being sufficiently reinforced to firmly hold the rod 13 against sagging.

In order to support the usual form of shade from the same bracket construction a roller bracket 15 is provided in connection with the curtain supporting arm for the reception of the usual form of curtain roller 16, the inner end of the roller bracket 15 terminating in a body portion 17 which is integral with the bracket 15 and at right angles thereto, the edges of the body portion 17 being crimped to form channels 18 for the reception of the outer arm of the anchoring member 4, the bracket 15 being slidable and consequently adjustable on the anchoring member 4, so that rollers of varying lengths may be accommodated. As shown in the drawings there are but three parts to each bracket and said parts are preferably stamped from sheet metal, consequently the brackets may be very cheaply manufactured and at the same time rendered sufficiently strong and durable for practically all purposes.

It will further be seen that by constructing the channels on parts of the bracket structure for sliding engagement with other parts thereof, the brackets may be adjusted for accommodating them to frames of varying widths and for shade rollers of varying lengths, and by providing the angular extensions for engagement with the edge of the frame the face of the frame will not be marred or injured in putting up or removing the brackets.

Having thus fully described my said invention, what I claim as new and desire to secure by Letters Patent, is:

1. A combined shade and blind holder

comprising a pole supporting arm, a downwardly extending body portion integral with said pole supporting arm and having a lateral extension for engagement with one edge of a frame, an anchoring member having channels for engagement with one end of the body, said anchoring member comprising parallel sections, and a roller supporting bracket having channels formed by bending over the edges of the bracket for engagement with one of the sections of the anchoring member.

2. In a combined shade and blind holder, a pole supporting arm, a rod supporting pin at the free end of said arm, a body portion integral with said arm and extending laterally in each direction from the arm, an anchoring member having at one end its edges bent over and forming channels for sliding engagement with said body portion, a roller supporting bracket, having at one end its edges bent over and forming channels for adjustable engagement with said anchoring member, and means for securing said arm and anchoring member to parts of a frame.

3. A combined shade and blind holder comprising an anchoring member bent upon itself to form parallel sections, one of said sections having channels formed at its edges, a pole supporting arm, a body integral with said arm and having adjust-

able connection with the channels of the anchoring member, said arm having a bowed portion adjacent its free end, a pin formed at the extremity of said arm and integral therewith, a roller supporting bracket, a body integral with said bracket and having channels for engagement with one section of said anchoring member, and means for securing the anchoring member and arm to a frame.

4. A combined shade and blind holder comprising a pole supporting arm, a body portion secured thereto and having means at one end for engagement with one edge of a frame, an anchoring member having channels for engagement with one end of the body portion, said anchoring member comprising parallel sections secured together at one end and separated at their opposite ends, and a roller supporting bracket having channels for sliding engagement with one of the sections of the anchoring member.

In witness whereof, I have hereunto set my hand and seal at Indianapolis, Indiana, this 8th day of November, A. D. nineteen hundred and twenty.

WILLIAM DUNSON. [L. S.]
